SIGNORS TO BOHN ALUMINUM AND BRASS CORPORATION, OF DETROIT, MICHIGAN,
A CORPORATION OF MICHIGAN

APPARATUS FOR COATING BEARINGS OR THE LIKE

Application filed April 26, 1926. Serial No. 104,755.

The invention relates to the coating art and refers more particularly to an improved method and apparatus for coating bearings or the like preparatory to the application 5 of the usual babbitt or other lining material. Brass or similarly alloyed bearings cannot readily be lined with babbitt without first coating the bearings with tin or like material. Thus by subjecting the bearings to a solution 10 of molten tin, the tin acts chemically on the brass replacing the copper of the brass. Bearings cast in the usual manner contain a certain amount of air and moisture, water frequently being present in amounts of 15 from ten to fifteen drops in a casting of the size ordinarily employed for connecting rod bearings of motor vehicle engines. The presence of this amount of moisture and air makes the bearings float in the tin bath until the 20 air and moisture are driven out, at which time, the bearings will be of such relative density as to sink in the tin bath. The higher the temperature of the tin bath the more accelerated is the chemical action of the tin 25 coating and the more accelerated is the loading of the solution with the copper from the brass bearings. As the solution becomes loaded with the copper the temperature must be raised in order to obtain effective coating 30 since the presence of copper in increasing amounts in the solution renders the same less active. It is important, therefore, to keep the temperature of the tin solution down. However, the lower the temperature of the 35 tin bath the slower is the process of driving off the water and the air in the casting with the result that there is a tendency to remove the bearings from the tin solutions before they sink, the bearings under such conditions 40 not being properly coated with the tin.

One of the objects of the invention is to provide a method and machine for coating the bearings wherein the bearings are automatically removed from the tin bath upon their 45 sinking, at which time the tin coating will be just right with the air and water driven out of the casting and the castings will also be thoroughly heated.

A further feature of the invention resides 50 in the provision of a machine for automatical-

ly moving the bearing castings from an acid treating tank to a tin coating tank and thence to a cooling tank. The invention also provides these tanks in the form of separate units with separate conveying means for each 55 unit whereby, for example, the conveyor which is subjected to the acid does not come into contact with the tin solution or the cooling solution. Likewise, the several other conveyors which contact with the cooling solution and tin solution do not come into contact with the solutions of the other tanks. Thus, the pedals carried by the several conveyors are not subjected to the successive varying 60 temperatures and chemical actions of the 65 different solutions as would be the case where the pedals of a single conveyor contacted successively, in moving the bearings, through the different solutions.

A still further feature of the invention resides in the construction of the bearing troughs and the pedal construction for moving the bearings along the troughs preventing clogging of the bearings in the trough or between the trough and pedals. Such a construction is very important since, if the bearings become clogged or jammed in the troughs, the conveyor mechanism, or other part of the operating mechanism become damaged requiring temporary shutting down of 70 the machine for repair. With our construction a large number of bearings are accommodated since there is no possibility of clogging. 75

With these and other objects in view, the 80 invention resides in the novel features of construction and combination and arrangements of parts as more fully hereinafter described and claimed.

Referring to the drawings in which like reference characters indicate corresponding parts:

Figure 1 is a plan view showing the machine;

Figure 2 is a side elevational view thereof showing in detail the acid bath apparatus;

Figure 3 is a similar view showing in detail the tinning bath apparatus;

Figure 4 is a similar view showing in detail the water bath apparatus;

Figure 5 is a detail side elevation view of a fragment of the endless chain carrier showing a pedal applied thereto;

Figure 6 is an elevation view at right angles 5 with the chain fragment as shown in Figure 4.

Figure 7 is a detail sectional view taken substantially on the plane indicated by line 7—7 in Figure 1;

Figure 8 is a sectional view taken on line 10 8—8 in Figure 1;

Figure 9 is a sectional view taken on line 9—9 in Figure 1 and

Figure 10 is a sectional view taken on line 10—10 in Figure 1.

15 The machine preferably comprises a plurality of units A, B and C sufficient in number to accommodate the various steps involved in the tinning operation. For simplicity and convenience of manufacture, these units are 20 preferably substantially identical in general construction, the unit B as shown in Figure 3 being typical. Thus the units are constructed of a trough 10 substantially V-shaped and supported by suitable standards 11 which 25 comprises the main supporting frame of the machine. 12 denotes a channel guide for the carrier, this guide being positioned above the trough 10 and following the general direction of the trough. Guided within the channel 30 12 is a carrier 13 which is of a chainlike endless carrier, this carrier at one end passing around the idler sprockets 14 and at the other end passing around the power driven sprockets 15.

35 16 represents a suitable source of power such as a motor which drives the main power shaft 17 preferably through a reduction gearing 18. The power shaft 17 imparts rotative power directly to the drive sprockets 15 of the unit A and also to the drive sprockets 40 of the unit B through gearing 19 and shaft 20. Likewise, the drive sprockets of the unit C are driven from shaft 20 through gearing 21 and shaft 22 as will be readily understood.

45 Referring again to the typical unit B the carrier 13 thereof is provided at suitable spaced points throughout its length with 50 pedals 23, which as shown in Figures 5 and 6, particularly, are secured by suitable anchors 24 to the desired links of the carrier chain. These pedals are also preferably substantially V-shaped to conform with the trough 10, the guide 12 being constructed in 55 relation to the trough so as to guide the pedals 23 within the trough and slightly spaced therefrom whereby the bearings or the like are moved longitudinally of the trough.

60 The trough 10 of each unit is formed at one end with a bearing receiving portion 25 and at the other end with a downwardly inclined bearing discharge portion 26, the portion 26 of each trough being positioned to 65 discharge the bearings from the trough of

one unit to the receiving portion 25 of the adjacent unit. Intermediate the end portions 25 and 26 the troughs 10 have a downwardly extending portion 27 which serves to lower the bearings into the tanks 28, 29 and 30 of the units A, B and C respectively. In the tank 28 is a suitable substance such as zinc chloride providing an acid bath for the bearings preparatory to their introduction into the tank 29 of the unit B. In this latter tank, 70 is placed the tin bath which is maintained at the desired molten temperature by suitable heating means such as the gas burner 31. For reasons aforesaid, it is desirable to maintain the temperature of the tin bath at approximately less than 650° F. The tank 30 is adapted to contain a suitable substance for cooling the bearings such as water.

75 As the bearings leave the trough 10 associated with the acid bath in tank 28 of unit A, it is desirable that all excess acid be freed therefrom so as to reduce the quantity of acid used and to prevent the same from being carried in large quantities to the tinning bath. Each bearing is freed from all excess acid, such as might adhere thereto in the form of drops, upon its discharge into the receiving end 25 of the trough 10 associated with the tinning bath. By particular reference to Figure 8 it will be noted that the discharge end 26 of the acid bath trough 10 is in a higher plane than the receiving portion 25 of the tinning bath trough 10 so that the bearings tumble down into the trough 10 by gravity and strike the sides thereof with sufficient force to free or knock off this excess acid. This acid collects in the bottom of the trough and passes therefrom through one or more openings 35 into the receiving portion 36 of a gutter or trough arranged thereunder. One leg 37 of this receiving gutter extends laterally with respect to the leg 36 to a point over the acid bath trough 28 whereby the collected excess acid is returned to this trough. If desired, the leg 37 of the collecting gutter 100 will be slightly inclined to facilitate the flowing of this accumulated acid back to the trough 28.

105 As the bearings leave the tinning bath in tank 29 they frequently carry excess amounts of tin in the forms of drops or accumulations and obviously it is also desirable to free the bearings from this excess tin, not only for the purpose of making the tin coating more uniform throughout but also for the purpose of economizing in the tin. The discharge end 26 of the trough 10 associated with the tin bath is arranged in a higher plane than the receiving end 25 of the trough 110 120 125 130 10 associated with the cooling bath so that as the coated bearings leave the tinning bath and discharge into the receiving end of the cooling bath trough, they tumble by gravity downwardly on to the cooling bath trough and strike the same with considerable force

sufficient to knock off or free the same from the accumulated excess tin. This tin collects in the bottom of the trough 10 and passes through one or more apertures 38 into an ingot 34 arranged thereunder. This ingot is removably supported so that as the same becomes filled with the accumulated excess tin it may be removed and dumped into the tinning bath tank 29.

It is important that the temperature of the tinning bath trough 10 and of the receiving end of the cooling bath trough be maintained at such a temperature as to prevent the solidifying of any of the tin bath which might come in contact therewith either by reason of the splash of the tin as the bearings tumble into the tank 29 or by reason of the tin carried by or freed from the bearings as they leave the tank. Obviously that portion of the trough 10 in immediate proximity with the heating means associated with the tinning bath will be maintained at this desired high temperature but in addition to this heating means we provide one or more additional burners 40 arranged in proximity to that portion of the tinning bath trough immediately adjacent the entrance end of the tank 29 so that tin splashed thereon as the bearings tumble into the bath will be maintained in a molten state and flow back into the tank 29. In addition we provide one or more burners 41 for heating the discharge end 26 of the tin bath trough and also burners 42 for heating the receiving end of the cooling bath trough. Thus the tin carried on to the discharge end of the tinning bath trough will be maintained in a molten state so as to flow therefrom by means of the burners 41 while the tin freed from the bearings as they tumble into the receiving end of the cooling bath trough will be maintained also in a molten state so that it may readily flow through the openings 38 to the ingot 34. Obviously, if desired, and it will probably be considered more practical, these burners 40, 41 and 42 will be partially or completely enclosed not only for the purpose of protection but for conservation of the heat. It will furthermore be noted that the discharge end 26 of the tinning bath trough is spaced from the receiving end 25 of the cooling bath trough to provide a draft passage 43 for the flames from the adjacent burners.

In operation the bearings are placed on the receiving portion 25 of the trough 10 of the unit A, the pedals 23 moving the bearings along the trough into the acid solution in tank 28, the speed of the carrier 13 being arranged to afford time for the desired chemical action during the travel of the bearings through the acid bath. The bearings are thereafter moved along the trough out of the tank 28 to the discharge end 26 where the bearings are automatically transferred to the adjacent receiving end 25 of the trough of

unit B. As previously mentioned, the bearings as they tumble from the trough of the unit A to the trough of the unit B strike this latter trough with sufficient force to free the same of any excess acid which may be clinging thereto which acid then passes through the opening 35 in the bottom of this latter trough into the gutter 36 and back through the leg 37 thereof to the acid tank 28. The pedals of the carrier associated with the unit B then engage the bearings and move them downwardly into the molten tin solution in the tank 29. Because of the water and air in the bearing castings, the bearings will, on their introduction to the tin solution, float, moving upwardly free from contact with the pedals 23, the pedals being carried beyond the floating bearings. It will be noted that the portions 23' which connect the pedals 23 with the carrier chain are relatively narrow as seen in Figure 6 whereby the floating bearings will be permitted to remain in the tin solution without being moved by the pedals. As soon as the moisture and air in the bearing castings has been driven therefrom, by reason of the molten tin, these bearings will sink in the tin solution and rest on the trough bottom where they will be picked up by the next on-coming pedal and moved along the trough out of the tin solution. Hence they will be discharged to the receiving end of the trough of the unit C. During the discharge of the bearings from the trough of the unit B to that of the unit C the bearings will be deposited with some force, into the trough of the unit C so that any excess tin carried thereby will be freed therefrom and flow through the apertures 38 into the ingot 34. In a similar manner the bearings are moved longitudinally of the trough of unit C into tank 30 containing the cooling water which serves to cool the bearings and discharge them at the end of the trough of this last unit in a condition permitting their immediate handling. The discharge end of the water bath trough is provided with a regulable discharge apron 44 pivotally connected as at 45 to a part of the machine structure and has associated therewith supporting segments 46 pivotally connected thereto as at 47 and extending through guides 48. A locking lever 49 is pivotally mounted to the frame of the machine for selective engagement with a plurality of notches 50 in the supporting segment. Thus the delivering apron 44 may be held in any of these angular or inclined positions by the engagement of the locking lever 49 with the desired notch 50. The bearings as they leave the discharge end of the cooling bath trough tumble downwardly along this apron 44 for depositing in any one of a number of containers placed upon the floor adjacent the end of the machine. With this construction the bearings may be directed to any of the several containers arranged at

various distances from the machine so that as one container becomes filled the apron may be adjusted to direct the bearings to another container while the filled container is being removed and replaced by an empty one. The locking lever 49 is preferably arranged so as to be operable from either side of the machine and as the lever or levers engage the segment 50 by gravity and as the apron 44 tends to swing downwardly by gravity, the aforescribed adjustment may be accomplished with great rapidity.

Since the action of the tin solution reaches the proper point at the time of sinking of the bearings indicating that the air and moisture in the bearings have been driven off, it will be noted that we have provided means for automatically removing the bearings from the tin solution at the proper time without unduly slowing up the speed of the carrier 13 and without unduly heating the tin solution.

It will further be noted that providing the separate units A, B and C the pedals associated with the respective units do not contact with the solutions of the tanks associated with the other units.

The underlying principle of the present invention as disclosed in the illustrative embodiment herein shown and described, is capable of expression in numerous forms of construction and it should accordingly be understood that no limitation should be imposed upon the invention by reason of any of the details of construction or specific arrangements of parts herein shown and described. Reservation is therefore made to make such changes in the essential and all of the non-essential details of the invention as may come within the purview of the accompanying claims.

What we claim as our invention is:—

1. A machine for treating bearings or the like, comprising a plurality of separate units, each consisting of a trough for receiving the bearings and each comprising an endless pedal carrier, pedals carried by the endless carriers for moving the bearings along the troughs respectively, means for moving the endless carriers, and means associated with the troughs of adjacent units adapted to discharge the bearings from the trough of one unit to that of the other.

2. A machine for treating bearings or the like, comprising a plurality of separate units, each consisting of a trough for receiving the bearings and each comprising an endless pedal carrier, pedals carried by the endless carriers for moving the bearings along the troughs respectively, means for moving the endless carriers, means associated with the troughs of adjacent units adapted to discharge the bearings from the trough of one unit to that of the other, a tank positioned below each of said troughs for holding a bearing treating substance,

ing treating substance, said troughs having a portion extended into the tanks respectively for conducting the bearings into the substance in the tanks, and guide means for the endless carriers for causing said pedals to substantially follow the said paths of said troughs respectively. 70

3. A machine for treating bearing or the like, comprising a plurality of units, each consisting of a trough for receiving the bearings and each comprising an endless pedal carrier, pedals carried by the endless carriers for moving the bearings along the troughs respectively, means for moving the endless carriers, means associated with the troughs of adjacent units adapted to discharge the bearings from the trough of one unit to that of the other, a tank positioned below each of said troughs for holding a bearing treating substance, said troughs having a portion extended into the tanks respectively for conducting the bearings into the substance in the tanks, guide means for the endless carriers for causing said pedals to substantially follow the said paths of said troughs respectively, the 80 pedals of one of said endless carriers having the bearing engaging portions thereof adapted to travel substantially below the substance contained in the trough and tank of the corresponding unit so that the bearing floating 95 in said substance will be permitted to remain in the substance without being moved by the bearing engaging portions aforesaid of the pedals. 85

4. A machine for treating bearings or the like, comprising a plurality of units, each consisting of a trough for receiving the bearings and each comprising an endless pedal carrier, pedals carried by the endless carriers for moving the bearings along the troughs respectively, means for moving the endless carriers, means associated with the troughs of adjacent units adapted to discharge the bearings from the trough of one unit to that of the other, a tank positioned below each of said troughs for holding a bearing treating substance, said troughs having a portion extended into the tanks respectively for conducting the bearings into the substance in the tanks, and guide means for the endless carriers for causing said pedals to substantially follow the said paths of said troughs respectively, the 100 pedals of one of said endless carriers having the bearing engaging portions thereof adapted to travel substantially below the substance contained in the trough and tank of the corresponding unit so that the bearing floating 110 in said substance will be permitted to remain in the substance without being moved by the bearing engaging portions aforesaid of the 105 pedals. 115

5. A machine for treating bearings or the like, comprising a plurality of units, each consisting of a trough for receiving the bearings and each comprising an endless pedal carrier, pedals carried by the endless carriers for moving the bearings along the troughs respectively, means for moving the endless carriers, means associated with the troughs of adjacent units adapted to discharge the bearings from the trough of one unit to that of the other, a tank positioned below each of said troughs for holding a bearing treating substance, said troughs having a portion extended into the tanks respectively for conducting the bearings into the substance in the tanks, and guide means for the endless carriers for causing said pedals to substantially follow the said paths of said troughs respectively, the 120 pedals of one of said endless carriers having the bearing engaging portions thereof adapted to travel substantially below the substance contained in the trough and tank of the corresponding unit so that when the pedals pass through the said substance in the last said tank they will clear bearings floating in said substance above the trough bottom, but will engage bearings in the substance resting on the trough bottom so as to move the latter bearings along the trough to a point free of contact with the substance in the tank. 125

5. A machine for treating bearings or the like comprising a trough for receiving the bearings, a tank containing a substance for treating the bearings, said trough having a portion extended into the tank for conducting bearings into the substance in the tank, a 5 pedal carrier, a pedal having a bearing engaging portion disposed adjacent the bottom of the trough substantially below the normal level of the substance contained in the trough and a connection between said pedal and carrier adapted to clear bearings floating in said substance above the trough bottom.

6. A machine for treating bearings or the like comprising a trough for receiving the bearings, a tank containing a substance for treating the bearings, said trough having a portion extended into the tank for conducting bearings into the substance in the tank, a 15 movable pedal carrier, a pedal having a bearing engaging portion disposed below the normal level of the substance contained in the tank, and a connection between the carrier and pedal adapted to clear bearings floating in said substance above the trough bottom, the said bearing engaging portion being arranged adjacent the trough bottom so that it will engage bearings in the substance resting on the trough bottom and move the latter 25 bearings along the trough.

7. A machine for treating bearings or the like comprising a trough for receiving the bearings, a tank containing a substance for treating the bearings, said trough having a portion extended into the tank for conducting bearings into the substance in the tank, a movable pedal carrier, a pedal having a bearing engaging portion disposed substantially below the normal level of the substance contained in the trough and a connection between 35 the pedal and carrier adapted to clear bearings floating in said substance above the trough bottom, the said bearing engaging portion aforesaid of the pedal being arranged adjacent the trough bottom so that it will engage bearings in the substance resting on the trough bottom so as to move the latter bearings along the trough, to a point free from contact with the substance in the tank.

8. A machine for coating bearings or the like comprising a tank containing the coating material, a movable carrier, means for moving the carrier, a trough, a pedal movable with the carrier and engageable with the bearings to immerse the bearings in the tank and to remove them therefrom, said pedal having a bearing engaging portion disposed adjacent the bottom of the trough substantially below the normal level of the substance 45 contained in the tank so as to clear the bearings upon their insertion into the tank for a predetermined time and to thereafter engage the bearings and move them along the trough to a point free from contact with the coating 55 material.

9. A machine for coating bearings, or the like, comprising a tank containing the coating material, a trough having end portions free from contact with said coating material and an intermediate portion submerged therein, a movable carrier, a pedal movable with the carrier and engageable with the bearings to move them along a portion of said trough, and guide means for said carrier, the said pedal having bearing engaging portions arranged adjacent the bottom of the trough so that the bearing engaging portions of the 70 pedals will engage the bearings and move them along the trough into the tank and thereafter clear the bearings floating in the tank, but moving submerged bearings resting on the trough and conducting the latter bearings along the trough and out of the coating material.

10. A machine for applying a tin coating to bearings, or the like, including a plurality of separate units, comprising an acid containing tank, a molten tin containing tank, and a cooling liquid containing tank, and separate conveying means associated with each tank 75 for moving a plurality of the bearings successively into and out of the said tanks in the order named.

11. A machine for applying a tin coating to bearings, or the like, comprising an acid 80 containing tank, a molten tin containing tank, and a cooling liquid containing tank, said tanks being angularly arranged with respect to each other, means for moving a plurality of the bearings successively into and out of the said tanks in the order named, said means comprising endless carriers associated with each of said tanks, and pedals mounted on said carriers and engageable to move said bearings.

12. In combination with a substantially V-shaped trough for receiving a plurality of bearings or the like, a carrier, a guide for said carrier, said carrier being provided with a pedal having a portion engageable with the bearings for moving the same along the trough, said pedal portion being V-shaped to conform with the trough and being spaced therewithin whereby jamming of the bearings 95 in the trough is prevented.

13. In an apparatus for coating bearings or the like, two units each including a container for material for treating the bearings and means for introducing the bearings into said material; means for delivering the bearings from one unit to the other and for freeing the bearings from excess amounts of said material and means for collecting the material thus freed.

14. In a machine for coating articles, a plurality of angularly disposed units each including a container for material for treating the articles and separate conveying means associated with each unit for introducing the articles into the treating material and 100

for delivering said articles to the next unit.

15. In a machine for coating bearings and the like, a plurality of units each including a container for material for treating the bearings, and means associated with each unit for introducing the bearings into the treating material and for delivering said bearings to the next unit and an adjustable delivery means associated with the last unit.

16. In a machine for coating bearings and the like, a plurality of units each including a container for material for treating the bearings, means associated with each unit for introducing the bearings into the treating material and for delivering said bearings to the next unit, and an adjustable delivery means associated with the discharge end of one of said units.

17. In an apparatus for coating bearings or the like, two units each including a container for material for treating the bearings and means for introducing the bearings into the material; means for delivering the bearings from one unit to the other and means associated with the last mentioned unit for freeing the bearings from excess amounts of said material and conducting the same back to said first unit.

18. A machine for treating bearings or the like, comprising a plurality of units, each consisting of a trough for receiving the bearings and each comprising an endless pedal carrier, a pair of guides for the carrier positioned substantially above the trough and following the general contour thereof, pedals carried by the endless carriers and supporting the said guides for moving the bearings along the troughs respectively, means for moving the endless carriers, and means associated with the troughs of adjacent units adapted to discharge the bearings from the trough of one unit to that of the other.

In testimony whereof we affix our signatures.
